RADIO RECEIVER CONTROL

Filed July 24, 1928

2 Sheets-Sheet 1

The diagram illustrates a three-stage vacuum tube amplifier circuit. Stage 1 is a grid leak oscillator with a coil 9 and a diode 6. Stage 2 is a triode stage with a coil 10 and a diode 11. Stage 3 is a triode stage with a coil 10 and a diode 11. The output of stage 3 is connected to a load. A feedback line from the output of stage 3 passes through a coil 12 and a diode 13 to the grid of the first stage. The circuit also includes a ground connection and various biasing components.

RADIORECEIVER CONTROL

Application filed July 24, 1928. Serial No. 295,055.

This invention relates to improvements in devices for controlling the output signal volume of electrical signalling systems such as used for example in radio receiving apparatus, and relates more particularly to improvements in devices for controlling the output volume of such systems having multiple stage tuned radio frequency amplification.

While the invention in its broader aspects is applicable in general to signalling systems having a plurality of tuned circuits employing unilateral mutual impedances, such as vacuum tubes, as the coupling elements, it has a particularly useful application in radio receivers having tuned cascaded vacuum tube amplification with a single tuning control for all stages and in which also an auxiliary tuning device is used to bring the antenna coupling stage to resonance.

The principal object of this invention then is to provide novel and improved means for controlling the output signal volume of radio receivers of the general character set forth above.

In the attached drawings:

Figure 1 shows a typical radio receiving system to which the invention is applicable and illustrates one embodiment of our invention;

Figs. 2 and 3 are enlarged views illustrating the mechanical details of the apparatus, and

Figs. 4, 5, 6 and 7 are diagrams illustrating several alternative dispositions of circuit elements with which this invention is applicable.

The methods heretofore employed for controlling the output volume of radio receiving apparatus are generally undesirable for use in receivers employing vacuum tubes whose filaments are energized by alternating current. Practical results have been obtained, however, by means of a resistor system associated with the antenna circuit in conjunction with an auxiliary tuning device capable of compensating for any detuning effects caused by the use of antennas and antenna circuit elements of varying capacities. This method of control, however, while generally satisfactory, has been found to possess an inherent defect,

in that the output signal of the receiver, when tuned to a powerful station at a moderate distance, is of such high intensity that a satisfactory minimum of signal strength may be unobtainable in spite of the fact that the primary of the first radio frequency transformer may be practically short-circuited at the minimum setting of the volume control.

We have discovered satisfactory and inexpensive means for controlling the volume whereby the signal intensity may be reduced to a desired minimum without adversely affecting the action of the receiver, and whereby also a beneficial increase in apparent selectivity may be secured.

With reference to the drawings, Figure 1 shows a wiring diagram of the tuned radio frequency system of a radio receiver in which the various main tuning elements are actuated from a single or common control and in which the vacuum tube cathodes are energized by low potential alternating current. The main tuning means consists of a plurality of condensers 1 associated respectively with the grid or input circuits of the various tubes, and these condensers as indicated in broken lines are operatively connected so as to be adapted for simultaneous operation from a single control element. Means is also provided for bringing the antenna circuit into exact resonance, this consisting in the present instance of an auxiliary tuning device in the form of a condenser 2 paralleling the condenser 1 in the input circuit of the first radio frequency amplifying tube.

In addition to the normal system of the aforementioned type, the diagram shows neutralizing condensers 3 included, in the manner illustrated, to reduce the oscillation tendencies of the amplifier tube; plate bypass condensers 4, plate circuit resistors 5, and filament bypass condensers 6 being included for a similar purpose, and to reduce any extraneous disturbances occurring in this part of the circuit. The bilateral mutual impedance system including condensers 3 and the portion 7 of the transformer secondary winding between the indicated tap and the ground is adjusted to balance the bilateral mutual impedance

system including the interelectrode capacity 8 of the vacuum tube and the primary 9 of the transformer. These systems form a balanced electrical bridge and allow the vacuum tube to perform its function as a unilateral mutual impedance device, without disturbance due to energy present in the secondary 10 of the transformer. Condensers 11 are added to equalize any irregularities of the circuit capacities which might otherwise cause the tuned circuits to tune to frequencies differing among the various stages, and a terminal 12 is associated with the external energizing circuits which are so arranged as to apply the desired direct current cathode-grid and cathode-plate potentials in any customary manner. The volume control consists of a resistor system 13 preferably in the form of a potential divider associated with the antenna and with the primary of the first or input radio frequency transformer in the manner illustrated. In so far as described above, the system illustrated in Fig. 1 of the drawings presents no novelty over prior practice relating to radio receiving apparatus of this general character, and no detailed description of the system as a whole is necessary.

In the illustrated embodiment of the invention, we associate a switch 14 with the auxiliary tuning condenser 2 in such manner that in certain positions of adjustment of the auxiliary tuning condenser the grid of the first radio frequency amplifying tube is disconnected from its normal circuits in the manner shown and is connected to the grounded or zero-potential side of the circuit, while in other positions of this condenser, the aforesaid grid is connected in its normal circuit with the result that the auxiliary tuning device functions in a normal manner to bring its associated tuning circuit into close resonance. The switch 14 when in the first-mentioned position and as shown in Fig. 1, operates to ground the grid of the first radio frequency amplifying tube, thus rendering the tube ineffective as an amplifier while maintaining the normal average energization and the direct current interelectrode potentials substantially the same, and unbalancing the above-mentioned neutralizing system. The tuned secondary circuit of the first radio frequency transformer is now connected through the neutralizing condenser 3 to portion 7 of the grid circuit of the next radio frequency amplifying tube, to which portion a current can flow by reason of said unbalancing, thereby reducing the radio frequency amplification and, therefore, the output volume to a desired extent, and allowing the regular volume control 13 to control the volume of the reduced signal in the normal manner. It will be apparent, therefore, that the device provides two distinct ranges of operation, in each of which the volume control 13 is operative to regulate the volume as required. In

one of these ranges, the output signals range from a desired minimum to a moderate intensity, while in the other range the signal volume varies between a moderate intensity and maximum volume. Also, in the lower intensity range, the relative number of tuned circuits is increased in proportion to the number of amplifying tubes, as compared with the high intensity range, thereby obtaining a substantial increase in relative selectivity in accordance with well known principles.

In Figs. 2 and 3, we have illustrated one form of mechanical means by which our invention may be practiced. In this instance, we provide a switch consisting of contact members 15 and 16 and a blade 17 which normally is held out of contact with the member 15 and in contact with the member 16 by means of a spring 18. The blade 17 projects into the path of a contact flange 19 on the rotor 20 of the condenser 2 and is provided at its outer end with a shoe 21 which may be of insulating or conducting material and is so formed that when said flange comes in contact therewith, the blade 17 is elevated into contact with the member 15 and is withdrawn from the contact 16. It will be noted, however, that the flange functions to close the circuit 15-17 and open the circuit 16-17 through an angular movement of the rotor of approximately 180° during which the capacity of the condenser varies between its minimum and maximum, the circuit 16-17 being closed and the circuit 15-17 being open during the remainder of the rotative movement, and that by reversing the direction of said movement from the minimum capacity position, the capacity may be increased to the maximum while the latter condition of the circuits prevails. The condenser 2 is thus made effective for both ranges of control.

In Figs. 4, 5, 6 and 7, we have illustrated circuits similar to that shown in Fig. 1, but differing from the latter in the method of auxiliary tuning control and other details. In each instance, the circuit includes the device of the present invention. In Fig. 4, the auxiliary tuning device takes the form of a variometer 22 located in series with the antenna, which latter is connected through a condenser 23 directly to the volume control variable resistor 24. A switch 25 is connected between the ground and the grid of the vacuum tube which latter is also connected through a resistor 26 to the first tuned circuit. The switch 25 is operatively associated with the variometer, as indicated by broken lines, and in certain positions of the latter operates to ground the grid rendering the tube inoperative, and allowing the signals to be transferred to the succeeding circuits by means of interelement inductions and without amplification. A variation to be noted is that the suppressor resistor 26 connected as illustrated serves in the well known

manner to suppress the tendency of the tube to generate oscillations. Another variation is that the resistor 24 is so connected as to vary the proportion of the antenna current flowing in the first tuned circuit, thereby regulating the volume.

In Fig. 5, we have shown the antenna connected through a tap directly to the grid tuning coil of the first stage of radio frequency amplification. In this case, the auxiliary tuning device takes the form of a variable condenser 27, in series with the antenna, and this auxiliary tuning control is operatively connected with a switch 28 in a manner similar to that described in connection with Fig. 1 whereby in one part of the rotation of the condenser 27, the switch is made to disconnect the grid from the tuned circuit and to connect it to ground. The broken line 29, Fig. 5, serves to illustrate that it is expedient but not necessary either in this instance or in the other embodiments herein described to ground the grid when it is disconnected from the tuned circuit, an alternative connection being to a point of any desirable direct current potential; or the grid circuit may be left open. Another well known neutralizing system, 30—31, is utilized in this instance.

In Fig. 6, the auxiliary tuning device takes the form of a variometer 32 which is in series with the secondary of the input transformer, this variometer being operatively connected with a switch 33 arranged so that in given positions of the variometer, the switch connects the grid to ground. In this instance, it will be noted that the switch 33 is connected between the grid of the tube and a suppressor resistor 34 as an alternative to the connection in the neutralized type of circuit, as shown in Fig. 1. Fig. 6 also serves to illustrate possible paths of capacitive induction 35 and 36, by which the signal may be transferred to the second tuned circuit in the low intensity range position in the absence of a neutralizing condenser system.

The device of the invention is applicable also to other types of volume control, one such application being illustrated in Fig. 7 in which a variable resistor 37 is placed in series with the antenna and with the primary of the input transformer. In this instance, the auxiliary tuning device is similar to that illustrated in Fig. 1. Another variation to be noted is that a suppressor resistor 38, connected between the grid and the switch 39 has been substituted for the neutralizing system of Fig. 1.

The invention is applicable in principle to many forms of electrical signalling apparatus and is not limited in use to radio receivers; nor is the invention limited to the particular radio receiving apparatus and arrangements herein set forth for illustrative purposes. The invention is applicable, for

example, to receivers employing loop antennæ; and although in apparatus of the type illustrated an operative connection between the auxiliary tuning control and the volume range switch will be found desirable, by reason of the resultant reduction in the number of manual controls and an increased simplicity of operation, such operative connection is not essential to the functioning of the switch for the purpose described and the switch may be independently controlled. Similarly, the invention may be applied to receivers employing a multiplicity of independent tuning controls. The device may vary widely as to detailed form and as to its position in the electrical system with which it may be associated.

We claim:

1. In a signalling system, a unilateral mutual impedance device, a signal circuit preceding said device and a signal circuit succeeding said device, an electrical circuit including said unilateral mutual impedance device connecting said signal circuits, an electrical circuit independent of said device continuously connecting said circuits, and means whereby said first-mentioned electrical circuit may be rendered ineffective.

2. In a signalling system, a plurality of tuned circuits each including a tuning element, said elements being controlled by a common means, a tuning element auxiliary to one of said tuning elements, a unilateral mutual impedance device interposed between two of said tuned circuits, and adjustable means operatively associated with said auxiliary element whereby in one position of said means a portion of a signal transferred from one tuned circuit to a succeeding tuned circuit passes through said unilateral mutual impedance device, and in another position of said means substantially no portion of the signal passes through said unilateral mutual impedance device.

3. In a signalling system, a plurality of tuned circuits each including a tuning element, said elements being controlled by a common means, a tuning element auxiliary to one of said tuning elements, a unilateral mutual impedance device and a bilateral mutual impedance system each arranged to transfer energy from one of said tuned circuits to another of said circuits, said bilateral system being continuously effective, and means operatively associated with said auxiliary tuning element for rendering said unilateral mutual impedance device effective or substantially ineffective.

4. In a signalling system, a plurality of signal circuits, a selectively adjustable tuning element electrically associated with one of said signal circuits, a unilateral mutual impedance device having a control electrode connected to one of said signal circuits, and a switch mechanically associated with said

- adjustable element arranged to disconnect the said control electrode from the signal circuit and to substantially simultaneously ground the control electrode.
5. In a signalling system, a plurality of signal circuits, a unilateral mutual impedance device and external thereto a bilateral mutual impedance system each arranged to transfer energy from one of said signal circuits to another of said signal circuits, said bilateral system being continuously effective, and means for rendering said unilateral mutual impedance device effective or substantially ineffective.
6. In a signalling system, a plurality of signal circuits, a selectively adjustable tuning element electrically associated with one of said signal circuits, a unilateral mutual impedance device and a bilateral mutual impedance system each arranged to transfer energy from one of said signal circuits to another of said signal circuits, and means mechanically associated with said selectively adjustable tuning element for rendering said unilateral mutual impedance device effective or substantially ineffective.
7. In a signalling system, a plurality of signal circuits, a unilateral mutual impedance device and external thereto a bilateral mutual impedance system each arranged to transfer energy from one of said signal circuits to another of said signal circuits, said bilateral system being continuously effective and said unilateral mutual impedance device having a control electrode connected to one of said signal circuits, and means operative on the control electrode for rendering the unilateral mutual impedance device effective or substantially ineffective.
8. In a signalling system, a plurality of signal circuits, a unilateral mutual impedance device and external thereto a bilateral mutual impedance system each arranged to transfer energy from one of said signal circuits to another of said signal circuits, said bilateral system being continuously effective and said unilateral mutual impedance device having a cathode and an electrode connected to one of said signal circuits, and means for rendering ineffective said unilateral mutual impedance device while maintaining the direct current potential between the cathode and said electrode substantially the same.
9. In a signalling system, a plurality of signal circuits, a unilateral mutual impedance device and external thereto a bilateral mutual impedance system each arranged to transfer energy from one of said signal circuits to another of said signal circuits, means for connecting the unilateral mutual impedance device to an energizing source, and means for rendering ineffective said unilateral mutual impedance device while maintaining the normal average energization of the unilateral mutual impedance device.
10. In a signalling system, a plurality of signal circuits, a unilateral mutual impedance device and a plurality of bilateral mutual impedance systems, said device and each of said systems being arranged to transfer energy from one of said signal circuits to another of said signal circuits and one of said bilateral systems being continuously effective, and means for rendering ineffective said unilateral mutual impedance device and one of said bilateral systems.
11. In a signalling system, a plurality of signal circuits, a selectively adjustable tuning element electrically associated with one of said signal circuits, a unilateral mutual impedance device and a plurality of bilateral mutual impedance systems, said device and each of said systems being arranged to transfer energy from one of said signal circuits to another of said signal circuits, and means mechanically associated with said selectively adjustable element for rendering ineffective said unilateral mutual impedance device and one of said bilateral systems.
